UNITED STATES PATENT OFFICE.

BURNHAM C. STICKNEY, OF ELIZABETH, NEW JERSEY.

TYPE-WRITING MACHINE.

SPECIFICATION forming part of Letters Patent No. 576,285, dated February 2, 1897.

Original application filed July 28, 1892, Serial No. 441,464. Divided and this application filed June 17, 1895. Serial No. 553,014. (No model.)

To all whom it may concern.

Be it known that I, BURNHAM C. STICKNEY, a citizen of the United States, and a resident of Elizabeth, in the county of Union and State of New Jersey, have invented certain new and useful Improvements in Type-Writing Machines, of which the following is a specification.

This invention relates to that class of type-writing machines made the subject of an application filed by me July 28, 1892, Serial No. 441,464, patented April 7, 1896, No. 557,711, and is a division thereof, and it also relates to that class made the subject of an application filed by me February 17, 1893, Serial No. 462,689, but embodying a different specific construction.

It consists in the features of construction and combinations of devices hereinafter more fully described, and particularly pointed out in the appended claims.

In the accompanying drawings, Figure 1 is a vertical longitudinal section of a type-writing machine embodying my present improvements. Fig. 2 shows the positions assumed by the parts when the type-bar and its associated mechanism have returned to their normal positions, the finger-key being still in its depressed position. Fig. 3 is a vertical longitudinal section on a larger scale and in slightly-modified form, showing the position of the parts just after the tripping act has taken place, the type-bar being in its printing position and the key in its depressed position; and Fig. 4 is a horizontal section taken at the line Z Z of Fig. 3, looking in the direction of the arrow and showing a portion of the key-levers broken away.

In the several views the same parts will be found designated by the same numerals of reference.

1 designates the framework of the machine; 2, the top plate or type-ring; 3, the type-bars; 4, the connecting-rods, and 5 the usual power-driven paper-carriage. The paper-carriage is provided with a feed-rack 6, with which operates a spacing-dog 7 and a detaining-dog 8, mounted upon a trunnion or rocker 9, held by a bracket 10 and actuated by a link 11, connected at its lower end to an arm 12, secured to a transverse rock-shaft 13,

mounted in the base of the machine at 14 and provided on each side with forwardly-extending arms 15, the front ends of which are united by a universal bar 16, extending transversely of the machine parallel with said rock-shaft 13 and arranged beneath a series of levers 17, pivoted at their forward ends to a transverse fulcrum-rod 18 and having a uniform motion. The connecting-rods 4 incline inwardly, and their lower ends terminate in a line transversely of the machine and are pivoted at 19 to the levers 17 in rear of the fulcrum-rod 18.

The escapement or spacing mechanism may be of any usual or suitable construction. A spring 20 is provided to return the universal bar of the spacing mechanism to normal position after release, as will presently appear.

Above the levers 17 are arranged key-levers 21, pivoted at their rear ends to a transverse fulcrum-rod 22, provided at their forward ends with keys 23 and bearing between their ends pivoted trips 24. Springs 25 are provided to return the key-levers to normal position upon being relieved from finger-pressure.

The trip 24 is pivoted to the key-lever at a point 26 in rear of the center of the machine (considered transversely) and is provided with an arm or lug 27, which normally and during the descent of the key-lever bears against a pin 28 upon the key-lever, being at this time held against said pin by the pressure of spring 29, arranged between the key-lever and the trip.

The lower end of the trip is arranged to bear upon the rear end of the type-bar-operating lever 17 to actuate and release the same and its connected type-bar and the universal bar. A pad 30 is provided beneath the key-levers to arrest their motion after release of the type-bars.

In operation, when a key-lever 21 is depressed, the trip 24 bears down upon the rear end of lever 17, depressing it and carrying down its associated connecting-rod 4, vibrating the type-bar 3 toward the platen. During its depression the lever 17 forces down the universal bar 16, depressing the arms 15, rocking the shaft 13, vibrating the arm 12 upwardly, and through the link 11 actuating

the feed mechanism. Through the feed mechanism described or any other suitable feed mechanism the carriage is fed the necessary letter-space distances as the impressions are made. At a predetermined time the lever 17 and its associated type-bar, together with the universal bar 16 and the feed mechanism, are released from the control of the key-lever and returned to their normal positions independently and in advance of said key-lever, all as will be now more specifically described. During said actuation of lever 17 by trip 24 the latter moves rigidly with the lever 21, being held against the stop 28 on said lever by the spring 29. The active lower end of the depending trip 24 therefore moves in a path described by an arc of a circle drawn from the pivot 22 as a center, as indicated by the dotted line *a*, while the rear contacting end of the lever 17 moves in a path described by an arc of a circle drawn from its pivot 18 as a center, as indicated by the dotted line *b*. It will be seen that these arcs diverge and intersect each other, and this point of intersection represents the point of disengagement between the trip and the lever 17 and which occurs just before the type strikes the paper on the platen. By reason of such divergence and intersection the trip 24 slides off of the lever 17 after depressing it, and thereby releases the same, Fig. 3, and permits it, together with its associated type-bar and the universal bar and spacing mechanism, to resume their normal positions independently of the key-lever 21, which is still depressed, as shown at Fig. 2, whereupon other key-levers may be manipulated without relieving the first key-lever from finger-pressure. Upon relieving the key-lever 21 from pressure it resumes its initial position under the return pressure of spring 25, during which motion the trip 24 rides along the end of lever 17 and vibrates independently on its own pivot against the tension of the spring 29, and upon rising above said end of lever 17 it vibrates forwardly under pressure of spring 29 and resumes its initial position with the lug resting against the stop 28, as shown at Fig. 1. It will be seen that the top and bottom edges of the lever 17 in Figs. 1 and 2 are parallel for the entire length of the lever and that the trips are formed with jogs or shoulders at their lower active ends, while at Fig. 3 the lever 17 is beveled at its rear end, and the lower end of the trip is parallel-sided; but these differences are not material in so far as my present improvements are concerned, since I do not wish to be limited in any wise to any peculiarity of construction or form of either the lever or the trip not specifically set forth in the claims.

What I claim herein as new, and desire to secure by Letters Patent, is—

1. In a type-writing machine, the combination with a type-bar of a type-bar-operating lever connected thereto, and a key-lever carrying a vibratory trip and a stop and a spring,

the said trip in the descent of said lever being held rigidly by said spring and stop and contacting with said type-bar-operating lever, and the said trip also vibrating in an arc about the pivot of the said key-lever, until by divergence it parts company with said type-bar-operating lever, substantially as set forth.

2. In a type-writing machine, the combination with a type-bar of a lever for operating the same and a key-lever carrying a pivoted trip adapted to actuate the type-bar-operating lever and to detach itself therefrom by divergence, and means for holding said pivoted trip rigid during the time it is actuating said type-bar-operating lever and detaching itself therefrom, substantially as set forth.

3. In a type-writing machine, the combination of a type-bar, a lever connected thereto, and a key-lever, the said key-lever and the said type-bar lever having each separate fulcrums, and the key-lever having a part adapted to contact with the type-bar lever, the said part and the said type-bar lever vibrating in arcs which intersect each other, and the said part separating from said lever in the downward movement at the point of intersection of said arcs, substantially as set forth.

4. In a type-writing machine, the combination of a lever connected to a type-bar, a key-lever having a trip jointed thereto and adapted to bear at one end upon said type-bar lever, the said trip being held rigidly during the downward movement of the key-lever and operating to depress the type-bar lever and to slide along and off the same, whereby the type-bar and its associated lever may return to normal position independently and in advance of the key-lever, and whereby during the return of the key-lever to its normal position said trip may vibrate and resume its proper position relatively to the type-bar lever, substantially as set forth.

5. In a type-writing machine, the combination with a circular series of type-bars of a series of rods attached at one end to the type-bars and at the other end to a series of operating-levers, the lower ends of the rods being arranged in a straight line, and a series of key-levers separably connected to said type-bar-operating levers, substantially as set forth.

6. In a type-writing machine, the combination with a circular series of type-bars of a series of rods depending therefrom and terminating in line transversely of the machine and connected at their lower ends to a series of operating-levers pivoted at one end and having uniform motion, a series of key-levers, and a series of trips between the key-levers and the type-bar-operating levers, substantially as set forth.

7. In a type-writing machine, the combination with a circular series of type-bars of a series of rods depending therefrom and terminating in line transversely of the machine and connected at their lower ends to a series

of operating-levers pivoted at one end and having uniform motion, a universal bar of the spacing mechanism adapted to be actuated by said levers, a series of key-levers, 5 and a series of trips between the key-levers and the type-bar-operating levers, substantially as set forth.

8. In a type-writing machine, the combination with a circular series of type-bars of a 10 series of rods depending therefrom and terminating in line transversely of the machine and connected at their lower ends to a series of operating-levers pivoted at one end and having uniform motion, a series of key-levers,

a series of pivoted trips between the key-levers and the type-bar-operating levers, and means for holding the trips rigidly upon their levers during the release of the type-bar-operating levers from the key-levers, substantially as set forth. ²⁰

Signed at New York city, in the county of New York and State of New York, this 15th day of June, A. D. 1895.

BURNHAM C. STICKNEY.
